ELECTRIC PLUG

Max M. Guernsey, Steilacoom, Wash.

Application May 13, 1947, Serial No. 747,613

4 Claims. (Cl. 173—361)

1

This invention relates to electric plugs adapted to be attached to the four wires from the terminal box of an electric motor, and especially to such a plug as may be connected to either a 110-volt or 220-volt supply circuit and will automatically make connections between either of said supply circuits and the proper wires to the motor, and more particularly is an improvement on the form of plug patented by me on March 25, 1947, numbered 2,417,928.

The objects of my invention are to improve the construction of such a plug as illustrated in my said patent, whereby the plug is made stronger and more substantial; whereby the exposed terminal prongs cannot be incorrectly inserted in the particular circuit outlet; whereby a ground connection is provided for the 220-volt outlet; which is simple in construction and unfailingly makes the correct motor connections for the particular supply circuit to which it is to be applied; and in which the attaching screws for the several motor wires are conveniently located and are of ready access for tightening.

I attain these and other objects as will readily appear to those familiar with the art, by the devices, and arrangements illustrated in the accompanying drawings, in which:

Fig. 1 is a plan view of the end of the plug, with its cover removed; Fig. 2 is a vertical cross-section thereof, taken on the line 2—2 in Fig. 1; Fig. 3 is a similar view, taken on the line 3—3 in Fig. 1; Fig. 4 is a plan view of the 220-volt side of the insert member; Fig. 5 is a similar view of the 110-volt side thereof; Fig. 6 is a side elevation of the insert member; Fig. 7 is a section thereof taken on the line 7—7 in Fig. 6; Fig. 8 is a plan view of the cover; and Figs. 9 and 10 are diagrammatic views of the connections between the motor wires and the contact prongs for the 110-volt and 220-volt supply circuits, respectively.

Similar numerals of reference refer to the same parts throughout the several views.

Small electric motors are adapted to be connected either to a 110-volt or to a 220-volt supply circuit and are provided with four live wires leading from the motor terminal box to the plug by which they make connection with the outlet of the supply circuit, said terminal box being suitably connected to the several parts of the motor. These wires, together with a ground connection wire 100, are illustrated diagrammatically in Figs. 9 and 10 and may be identified herein by the numerals 101, 102, 103 and 104.

In order to connect the motor to a 110-volt

5 circuit, the wires 101 and 102 must be connected to one side of the supply circuit, while the wires 103 and 104 are similarly connected to the other side thereof. This connection is accomplished within my plug when the prongs thereof adapted to enter the contact outlet of a 110-volt supply circuit are extending from the plug.

Similarly, when it is desired to connect the motor to a 220-volt supply circuit, the wires 102 and 103 are connected together, and the wire 101 is connected to one contact prong and the wire 104 is connected to the other prong, while the ground wire 100 is connected to a third contact prong.

15 The main body 10 of the plug is formed of hard rubber, or of other suitable insulating material, and may be oblong in plan, with rounded ends as seen in Figs. 1 and 8, and its interior is divided into three distinct chambers connected together.

20 The chamber 14 is preferably cylindrical in form and forms the entrance passage by which the five wires of the motor enter the plug.

25 Immediately above the chamber 14 I form a central chamber 12, which is deep enough to receive the prongs of the insert member hereinafter described. This chamber 12 is provided with a metallic contact 13, extending upright therein and adapted to contact the ground prong of the 220-volt side of the insert member, as hereinafter described.

30 This contact plate 13 is electrically connected by a suitable conductor to a terminal 14 on the outside of the plug 10, said terminal 14 being adapted to be connected to a suitable ground. 35 This chamber 12 is of such form as to receive the several prongs of the insert member and is, in general, rectangular in form (Fig. 1) but with two side cavities 15 adapted to receive the inclined prongs of the 220-volt side of the insert member.

40 The upper chamber 16 is adapted to receive the insert member, the contact prongs of one side thereof extending down into the chamber 12, while those of the other side thereof project upward through suitable openings in the cover 17, which is removably secured to the body 10 and which closes the said chamber 16. This chamber 16 is larger than the chamber 12, thus leaving a shelf 18 extending around three sides thereof. 45 The form of the chamber 16 follows closely that of the body 10 except at one end which is not curved, thus preventing the similarly shaped insert member from being incorrectly inserted therein.

50 This shelf 18 has five metal plates secured

thereon, each of which extends up the sides of the chamber. The part of the said plates resting on the shelf 18 is provided with a screw by means of which the wires from the motor are attached to the plates.

The ground wire 100 is thus attached to the plate 19; the wire 101 is fastened to the plate 20; the wire 102 is fastened to the plate 21; the wire 103 is fastened to the plate 22; and the wire 104 is fastened to the plate 23. The plates 20 and 23 are located on opposite corners of the same side shelf 18; and the plates 21 and 22 are located near the center of the shelf 18 on the opposite side of the chamber 16. The ground wire 100 leads from the motor and is fastened to the plate 19 which is located at the center of the curved end of the chamber 16. As above described, a second ground plate 13 is secured in the middle of the same end of the chamber 12 and has a connection leading through the body 10 to a terminal screw 14, to which a grounding wire may be secured.

These contact plates 20, 21, 22 and 23 are positioned in the sides of the outer chamber 16 in staggered relation on the two opposite sides of the chamber so that, when the hereinafter described insert member is inserted into the outer chamber, the side plates thereof will contact different contact plates when one set of prongs thereof are exposed for use, than when the other set of prongs are exposed for use, thus making different connections within the said insert member between the exposed prongs and the motor wires, to suit the different voltages of the supply circuits.

The insert member 24 comprises a body made of hard rubber or other suitable insulating material, shaped to fit neatly in the upper chamber 16. The insert member has two prongs 25 and 26 extending in parallel positions from one side thereof; and two other contact prongs 27 and 28, set at an angle to each other, extending from the opposite side thereof.

The insert member 24 is also provided with a third, or ground, contact prong 29, extending from the same side as the said prongs 27 and 28, and which is adapted to ground the outlet when the insert member is set for the 220-volt supply circuit.

All the above contact prongs extend into the insert member to the central plane thereof. This central plane is illustrated in Fig. 7 of the drawing, showing the ends of the several prongs 25, 26, 27, 28 and 29. The sides of the insert member are provided with five contact plates which are connected by suitable conductors to the several prongs as follows: The prong 25 is connected to the side plates 30 and 31 at the upper corners of the insert member, and also to the prong 27. The prong 26 is connected to the side plate 32, which extends across the lower side of the insert member and around the two lower corners thereof, and this plate 32 is also connected to the prong 28. The prong 29 is connected to the plate 33 positioned at the center of the curved end of the insert member 24. An unattached side plate 34 is positioned at the center of the same side as the side plate 30.

When the motor is to be connected to the 110-volt supply circuit the two prongs 25 and 26 project through the cover 17 and are positioned to enter the corresponding openings in the 110-volt supply circuit outlet. The prong 25 thus connects to both the side plates 30 and 31, and these plates contact the plates 20 and 21 in the cham-

ber 16, to which the motor wires 101 and 102 are connected. The other prong 26 connects to the side plate 32, which contacts the plates 22 and 23 in the chamber and these plates are connected to the motor wires 103 and 104.

When the insert member is in this position the ground prong 29 extends down into the chamber 12 and the side plate 33 thereof contacts the grounded plate 19, while the prong 29 contacts the plate 13 which is connected to the ground terminal 14. When the insert member is in this position the said two other prongs 27 and 28 lie in the chamber 12, lying in the side cavities 15 therein. Thus it will be seen that the two wires 101 and 102 are joined together at the removable prong 25, through the plates 20, 30 and 21, 31; and that the wires 103 and 104 are similarly joined together at the prong 26 through the plates 22, 32 and 23.

When, however, the motor is to be connected with a 220-volt supply circuit the insert member 24 is inverted in position in the chamber 16, the three prongs 27, 28 and 29 project through the cover 17, and the prongs 25 and 26 lie in the central chamber 12. The ground prong 29 is connected to the end side plate 33 which contacts the ground plate 19, which is connected to the motor ground wire 100. The prong 27 is connected to the side plate 31 which contacts the plate 20 to which the motor wire 101 is connected; the prong 28 is connected to the side plate 32 which contacts the plate 23 to which the motor wire 104 is connected; and the motor wires 102 and 103, connected to the plates 21 and 22, respectively, are electrically joined together by the contact with the side plate 34.

Thus it will be seen that I have invented an improved plug in which the insert member must be in either of two inverted positions, and the contact plugs extending therefrom being such as to make the correct connections between the motor wires for the particular supply current voltage. It will be further observed that this form of plug is of very substantial and rugged construction and is suitable for practical use under factory conditions. Further, the fact that the outer chamber is larger than the central chamber, thus providing a shelf between the two chambers, not only gives a firm base for the insert member to receive the pressure from the exposed contact prongs when they are being inserted in the supply outlet, but also gives a horizontal base for the several contact plates 19 to 23 so that the screws securing the several wires of the motor to said plates act downward and are convenient of access by the screw driver when the several wires are being secured thereto, or the screws are being tightened thereon.

It is, of course, to be understood that changes may be made in the details of construction of the above described electric plug without departing from the spirit of my invention as outlined in the appended claims.

Having, therefore, described my invention, what I claim and desire to secure by Letters Patent, is:

1. An electric plug having a plurality of five wires leading from a utility adapted to use current of either of two different voltages, connected thereto and adapted to be connected to either of two supply circuits of different voltages, comprising a plug body; a central chamber in said body and having an entrance passage adapted to conduct said wires thereinto; an outer chamber having five insulated contact plates secured

therein, said wires being secured to said plates; an insert member of insulating material adapted to be placed in said outer chamber in either of two inverted positions; five contact prongs extending from the two opposite sides of said insert member, one set thereof extending into said central chamber and the other set thereof extending out from said plug for engagement with one of said supply circuits; insulated contact plates mounted on the sides of said insert member and connected to said contact prongs, and adapted to severally contact with said contact plates in said outer chamber, whereby the said contact prongs are electrically connected to said wires.

2. An electric plug as set forth in claim 1, wherein said outer chamber is of larger dimensions than said central chamber, thereby providing a shelf between the two said chambers, wherein said insert member is based.

3. An electric plug as set forth in claim 1, one of said five wires is a ground wire; wherein one of said contact plates is a ground contact plate mounted on the shelf in the center of the end of said outer chamber and connected to said ground wire; wherein one of the prongs is a ground prong extending from one side of said insert member; a side plate secured to the end of said insert member, and connected to said ground prong, whereby said ground plate in said outer chamber will engage said end side plate on the insert member when said insert member is in either of its two positions.

4. An electric plug, comprising a plug body; a chamber in the end thereof; a plurality of fixed plates mounted in said chamber, to which a plurality of wires are secured; an invertible insert member in said chamber; means to limit the position of said insert member in said chamber; a plurality of contact prongs extending from the upper and lower sides of said insert member; a plurality of side plates centrally mounted on the sides of said insert member, certain of said side plates being electrically connected to said prongs, said side plates being adapted to contact said fixed plates, whereby the relative contact between said fixed plates and the side plates, and the exposed prongs, are changed when the said insert member is inverted.

MAX M. GUERNSEY.
